UNITED STATES PATENT OFFICE.

COLIN BROWN, OF ROCHESTER, NEW YORK.

SPRAYING DEVICE.

Application filed October 7, 1926. Serial No. 140,000.

My present invention relates to spraying devices and more particularly to atomizers of the type usually used as hand sprayers for projecting liquids upon plants, or in corresponding environments for the purpose of reaching and killing bugs and insects. The invention is not necessarily limited to this use the statement being, merely that it is highly adaptable to devices of this kind. It 10 has for its object to provide a construction whereby atomizers and sprayers of this general nature may be manufactured at low cost, and yet be durable and efficient in their operation.

15 To these and other ends the invention resides in certain improvements and combination of parts, all as will be hereinafter more fully described, the novel features being pointed out in the claims at the end of the 20 specification.

In the drawings:

Figure 1 is a side elevation of an atomizer and hand sprayer constructed in accordance with and illustrating one embodiment of my 25 invention;

Figure 2 is a fragmentary side elevation of a portion of the pump cylinder with connecting parts;

Figure 3 is a top plan view of the device 30 shown in Figure 1;

Figure 4 is an enlarged sectional view of the forward end of the pump cylinder and its mounting on the reservoir; and

Figure 5 is a fragmentary section on the 35 line 5—5 of Figure 4.

Similar reference numerals throughout the several views indicate the same parts.

This invention contemplates the production of what is known as a "continuous atomizer," 40 namely, one in which a continuous spray results from the intermittent pulsations of a hand or other pump through the operations of which latter a pressure is created and maintained upon a fluid body that is ultimately projected from the device without 45 interruption, that is, continuously, not reflecting the pressure giving impulses of the pump. Such devices are largely used at the present day in the extermination of flies, a 50 suitable killing liquid being pumped directly upon these insects or into the atmosphere which they are frequenting. The liquid used is usually supplied in a can or reservoir 1 (referring more particularly to the drawings) having a pressed threaded neck 2 for 55 a screw top or stopper (not shown). The

idea is that the atomizing or pumping device of the present invention may be screwed down upon the neck 2 in place of the top or cap after the latter has been removed, for 60 which purpose my said device comprises a threaded cap 3 that is screwed down upon the neck 2 in the manner shown in Figures 1 and 4.

Extending through the top of this cap and soldered or otherwise secured therein, as indicated at 4 is a siphon tube 5 that extends to approximately the bottom of the can or reservoir 1 as shown in dotted lines in Figure 1. In the present embodiment this tube is 70 sealed at its upper end and, assuming that it is made from pieces cut from a continuous length of tubing, the sealing may be done by soldering the upper end at 6. The discharge portion of this upper end which projects above and exteriorly of the cap member 3 resides in an aperture 7 bored in the front of the tube near its top. Below the top wall 8 of the cap through which the atomizer tube projects is an opening 9 in 80 that tube that communicates with the chamber or body of air 10 lying upon the body of liquid 11 in the can or reservoir 1.

In the operation of the device the body of air 10 is under greater than atmospheric 85 pressure which pressure, acting on the body of liquid 11 to raise it in the tube 5, is generated by the hand pump now to be described.

This hand pump comprises a cylinder 12 90 consisting of an ordinary pump tube, the forward end of which is closed by a cap 13 or in any suitable manner. This forward end is soldered at 14 or otherwise suitably secured to the top of the cap member 3 so as to overlie the same for some distance at least as shown in Figure 4. Through this overlying portion, communication is had between the said forward end of the pump cylinder or tube 12 and the air pressure body 10 within the can or reservoir 1 overlying the liquid body 11 by means of a valve cage 15, the upper end of which has a small opening 16 and the lower end of which has an opening 17. A cotter pin or similar device spans the lower 95 opening 17 and supports a ball 18 that constitutes a check valve for the opening 16 in the well known manner of pump operation whereby air pumped under pressure to the chamber 10 maintains its pressure on the 100 liquid 11.

The pressure referred to is produced by

a pump embodying the cylinder 12 before referred to and a suitable pump piston 19 on a rod 20 connected to an exterior handle 21. It is easy to see that the operations or reciprocations of the piston 19 in the cylinder 12 will, through the check valve 18, build up a sustained pressure in a chamber 10. The result of this pressure is as follows:

First, it presses upon the body of liquid 11 10 in such manner as to cause it to rise in the tube 5, the latter being open to the atmosphere at 7. Secondly, the air escapes directly through the opening 9 just below the cap at the top and mingles with the rising column 15 of liquid with an atomizing effect whereby the desired spray issues from the discharge nozzle or opening 7, which spray is continuous due to the fact that the pressure at 10 is continuous as built up by the pump through 20 the check valve.

Applicant is aware that, as a matter of theory, it can be pointed out that the back pressure downwardly in the tube 5 because of the entrance of the compressed body of air 25 at 9 should equalize the driving pressure of the air body 10 upon the liquid body 11. However in practice this is found not to be the case. The liquid column continues to rise and the compressed air entering the atomizing tube 5 at 9 continues upwardly instead 30 of downwardly exerting its force and discharges at the nozzle aperture 7 in the manner previously stated.

The sprayer described and shown is a very 35 cheap one to make not only because of the fact that parts 5, 12 and 13, in assembling are all secured by soldering or otherwise upon the single cap element 3 but because their relationships, in assembling, do not have to be 40 fixed with any great degree of accuracy. The tube 5 may be high or low within certain limits as long as one opening 9 is below and the other opening 7 is above the cap top 8 without any particular reference to the position 45 of the cylinder head 13 or the cylinder 12. This is in contrast to the usual construction of atomizers in which an air opening in the pump must be carefully placed with reference to the mouth or discharge opening 50 of the atomizing tube.

It need hardly be necessary to further point out that, as a matter of manufacturing facility, the liquid to be used can be supplied in cans such as that shown at 1 with an ordinary screw cap closure corresponding to 55 the cap portion shown at 3 and then the latter substituted therefor, which in the one operation attaches the whole pump mechanism to the can or container.

I claim as my invention:

1. In a sprayer, the combination with a reservoir adapted to contain a body of liquid, and having a threaded neck thereon adapted to receive a screw cap, of a cap threaded on said neck, an atomizer tube extending through 60 said cap and secured therein, the lower end of the tube on the interior having an opening below the fluid level of the reservoir and another opening above the fluid level thereof and the upper end of the tube having an exterior atomizing spraying opening, and a hand pump cylinder secured to the exterior of the cap and a check valve comprising a casing secured through registering apertures provided in said cap and the side wall of 65 the pump cylinder and providing one-way communication from said pump to the interior of the reservoir to accumulate compressive pulsations of the pump and supply pressure to the top of the reservoir to create air 70 pressure therein above the liquid body, and to also escape, successively, through the said interior and exterior openings of the tube.

2. In a sprayer, the combination with a reservoir adapted to contain a body of liquid, and having a threaded neck thereon adapted to receive a screw cap, of a cap threaded on said neck, an atomizer tube extending through 75 said cap and secured therein, a hand pump cylinder secured to the exterior of the cap, and a check valve comprising a casing secured through registering apertures provided in said cap and the side wall of the pump cylinder and providing one-way communication 80 from said pump to the interior of the reservoir to accumulate compressive pulsations of the pump and supply pressure to the top of the reservoir to create air pressure 85 therein above the liquid body.

COLIN BROWN.
